POSTAGE METER LOCKOUT DEVICE
 Lewis C. Hill, Fremont, Calif. assignor to Friden, Inc.,
 a corporation of Delaware
 Filed May 3, 1965, Ser. No. 452,562
 5 Claims. (Cl. 192—8)

This invention relates to a metered mailing machine, and more particularly to a means for preventing fraudulent use of the meter.

The present invention is an improvement of a metered mailing machine of the type disclosed in Patent No. 3,107,854 issued to Ingemar H. Lundquist, Oct. 22, 1963. In this type of mailing machine the amount of prepaid postage to be printed on envelopes or on strips of tape for affixture on packages or other bulk mail matter is settable in the machine by a manual adjustment of the selector mechanism. Upon adjustment of the selector mechanism, the value is visually indicated and the type wheels in the rotary printing head are accordingly adjusted to printing position. At the same time, mechanism is conditioned to effect a positive and a negative registration of the value in the selector mechanism in the ascending and descending registers, respectively, of the machine upon initiation of the postage metering operation.

In postage meter machines of this type wherein ascending and descending registers are driven by a belt, or other similar drive means, it is important that the actuation of the registers be in synchronism with the cyclic rotation of the print-head. If, for any reason, the registration of the value in the two registers should be out of phase with the rotation of the print-head, a fraudulent impression may be effected without a registration of the postage value in the registers. Accordingly, it is an object of the present invention to provide a postage metering machine with an improved means for preventing fraudulent use of the meter upon an interruption of the register drive means.

Another object of the invention is to provide an improved means for preventing operation of a postage meter when the actuating means for the registers and the rotation of the print-head are out of phase one with the other.

Other objects and advantages will appear from the following description of a preferred embodiment as illustrated in the accompanying drawings, in which:

FIG. 1 is a fragmentary sectional plan view of the postage metering machine showing the meter drive means; and

FIGS. 2 and 3 are similar elevational views of the meter drive terminating means in each of two operational positions.

The invention is disclosed as embodied in a metered mailing machine of the type described in the above-mentioned Patent No. 3,107,854, having a base portion 10 (FIG. 1), a postage meter unit 12, detachably mounted on the base portion 10, and a drive mechanism within the base portion for controlling the synchronous cyclic rotation of the auxiliary print-head, generally indicated at 15, and the postage indicia print-head, indicated at 16. The auxiliary print-head 15 is supported within the framework of the base portion 10, while the indicia print-head 16 is suitably journaled within the postage meter unit 12, and each of the print-heads is positioned for cooperation with the endless conveyor belt 17 running within base portion 10. As each envelope is moved into engagement with the conveyor belt 17 for conveyance to the right in FIG. 1, a synchronous cyclic rotation of print-heads 15 and 16 is effected for the printing of a postmark impression on the envelope.

Upon securing the detachable postage meter unit 12 in

2

its attached, or operative, position upon base portion 10, the power-driven or actuating mechanism for the meter unit is operatively connected to the main drive unit, generally indicated at 20, secured on the main drive shaft 21 (FIG. 1). The indicia print-head 16 is supported between each of two shafts 22 and 23 journaled in meter unit 12. Shaft 22, at its one end, is secured to one end of the indicia print-head 16 concentric therewith, while shaft 23 is secured at one end to the other end of the indicia print-head 16 concentric therewith and coaxial with shaft 22. Generally, the actuating mechanism for the meter unit 12 comprises gear 24 rotatably mounted upon shaft 22 and enmeshed with the gear 25 of the driving unit 20, a notched disk 26 for cooperation with the Geneva wheel 27 of the driving unit 20 and a gear 28 adapted to become enmeshed with the mutilated gear 29 of the driving unit 20, the notched disk 26 and gear 28 of the actuating mechanism being secured on the indicia print-head shaft 22.

Upon engagement of the main drive clutch 34 (FIG. 1), the driving unit 20 becomes effective to control the cyclic operation of the postage meter unit 12 in a well-known manner and as fully described in the above-mentioned Patent No. 3,107,854. Rotation of the gear 25 of the driving unit 20 immediately becomes effective through gear 24 rotatably mounted on shaft 22, to release the indicia print-head 16 for a cyclic operation, as described in the above-mentioned patent. During this phase of the cyclic operation of the meter unit, the Geneva wheel 27, in cooperation with the notched disk 26, is effective to prevent rotation of the indicia print-head shaft 22, followed immediately by the meshing of the teeth of the mutilated gear 29 with the teeth of the associated gear 28 secured on the print-head supporting shaft 22 to impart a cyclic rotation thereto. Engagement of the main driving clutch 34 also effects cyclic rotation of the auxiliary print-head 15 in synchronism with the indicia print-head 16. Rotation of the auxiliary print-head 15 is controlled in the same manner as that of the indicia print-head 16, wherein the Geneva wheel 35, similar to the wheel 27, and the mutilated gear 36, similar to gear 29, is secured on drive shaft 21 and cooperate respectively with notched disk 37 and gear 38 secured on the shaft 39 which carries auxiliary print-head 15.

The engagement of the main drive clutch 34 is controlled by the frictional engagement of an envelope or other piece of mail matter with the left end of the endless belt 17 (FIG. 1) to initiate cyclic operation of the auxiliary print-head 15 and the indicia print-head 16 in timed relation to the movement of the envelope by belt 17, to the right as viewed in FIG. 1. As the leading edge of an envelope moves into engagement with the endless belt 17, the pressure foot 45 is also engaged thereby. Pressure foot 45 is secured on the outer end of clutch control shaft 46 and is positioned adjacent the edge of the belt 17 in a manner such that immediately upon engagement of the envelope with the endless belt 17, the subsequent movement of the envelope thereby rocks pressure foot 45 and therefore shaft 46 counter-clockwise as viewed from the lower end in FIG. 1. Upon such rocking movement of the shaft 46, the upstanding arm 47 secured thereon and pivotally supporting the left-hand end of clutch control link 48 moves the link 48 to the left to rock clutch-engaging bellcrank 49, thereby releasing the clutch 34 for cyclic rotation.

Following each cycle of rotation of the auxiliary print-head 15 and the indicia print-head 16, main drive clutch 34 becomes disengaged. To effect the disengagement of the clutch 34, the free end of the clutch control link 48 extends into the rotational path of the pin 50 carried by the driven side of the clutch. Following approximately

180 degrees of clockwise rotation of the clutch 34, as viewed from the bottom in FIG. 1, pin 50 engages the extended end of the control link 48, rocking it counter-clockwise about its pivotal connection with arm 47, thereby removing the tooth of the actively moved link 48 from engagement with the ear 51 of clutch-engaging bellcrank 49. Thus, bellcrank 49 is released to the urgency of its spring 52, rocking bellcrank 49 into clutch-disengaging position with respect to the clutch 34, whereupon clutch 34 becomes disengaged to terminate rotation of the print-heads 15 and 16. Main drive clutch 34 and therefore drive shaft 21 are driven in a well-known manner by an electric motor through a suitable slip clutch and the timing belt 53. The foregoing is believed to suffice for an understanding of the operation of the driving mechanism 20. However, for a more complete description reference is to be had to the afore-mentioned Patent No. 3,107,854.

As stated above, during each cycle of machine operation, the desired amount of postage as indicated in the selector register is imprinted upon a piece of mail matter, and this same value is subtracted from the value in the descending register and is also accumulated in the ascending register. As fully disclosed in the afore-mentioned patent, the registration of selected values in the descending and ascending registers is controlled by the rotation of actuator shaft 60 (FIGS. 2 and 3) in cyclic timed relation to the rotation of the postage indicia print-head 16. In order to maintain such cyclic timed relationship between the indicia print-head 16 and the register actuating mechanism, a toothed pulley 61 is secured on the outer end of the print-head shaft 23 and a similar toothed pulley 62, having an identical pitch diameter to pulley 61, is secured on the outer end of register actuator shaft 60, each of the pulleys 61 and 62 being drivingly connected by means of a timing belt 63. Tautness of the belt 63 is controlled by an idler arm 64 rockably mounted at its one end on a stud 65 secured on frame member 66 of the meter unit. At its other end, idler arm 64 carries a roller 67 which is resiliently maintained in engagement with the outer surface of belt 63 by means of a tension spring 68 which is suitably supported at its one end on the extension of the roller supporting pin 69 and at its other end on a pin 70 secured on frame member 66.

Each of the shafts 23 and 60, the indicia print-head shaft and register actuator shaft, respectively, rotate in synchronism. The toothed pulley 61 on shaft 23 becomes a driving pulley while pulley 62 on shaft 60 is the driven pulley. As the indicia print-head 16 is rotated approximately 210 degrees from its full-cycle position, the leading edge of the indicia die plate 71 moves into a suitable opening provided in the base of the meter unit 12. During the initial 210 degrees rotation of the shaft 23, or digitation phase of the cycle, the value in the selector mechanism is registered in both the descending and ascending registers. It will be noted that the opening in the base of the meter unit is conventional in size, i.e., its length is slightly greater than the axial width of the print-head 16 to permit rotation of the print-head therein, and its width is approximately two-thirds of the arcual length of the indicia die plate 71 so that only a portion of the die plate appears in the opening at any given time. The foregoing is conventional and is fully shown and described in the afore-mentioned Patent No. 3,107,854.

If, for any reason, the timing belt 63 should become broken or teeth should be stripped therefrom during this initial, or digitation, phase of the cycle, the amount of postage in the selector mechanism may or may not be registered in the descending and ascending registers, depending upon the angular rotation of the pulleys 61 and 62 at the time the operation of the belt is terminated. If the indicia print-head 16 is locked against rotation immediately following the initial 210 degrees rotation of the shaft 23, an impression will not be taken from the indicia die 71. On the other hand, should the belt 63

be broken, or its teeth stripped during the remaining 150 degrees, approximately, of the machine cycle, an indicia impression and the registration of the postage value in both registers will have been effected and a subsequent 5 machine cycle of operation will be precluded.

For the purpose of locking the meter drive means in either its full-cycle position or following a partial cyclic rotation thereof, due to the severance of the timing belt 63 or the stripping of the teeth therefrom, a three-arm bellcrank 75 (FIGS. 2 and 3) is provided and is pivotally supported on a stud 76 carried by frame member 66. Each of the two arms 77 and 78 of the three-arm bellcrank 75 lies in a plane parallel to and adjacent the outer surface of the toothed drive pulley 61 for cooperation 10 with a pin 79 secured on the side of the pulley. The free end portion of the arm 77 is formed to provide a shoulder or hook 80 for engagement with the pin 79 in the full-cycle position of drive pulley 61, the full-cycle position of the pin 79 being indicated by dash line in 15 FIG. 2. The angular relationship of the arms 77 and 78, one to the other, is such that in one of the two rocked positions of bellcrank 75, and upon normal counter-clockwise rotation of the drive pulley 61, the shoulder 80 of arm 77 will engage pin 79 in the full-cycle position 20 of the pulley 61. In the other rocked position of bellcrank 75, the square end of arm 78 will be positioned in the rotational path of the pin 79, whereby pin 79 will abut the end of arm 78 following approximately 210 degrees of the cyclic rotation of the pulley 61. Normally, bellcrank 75 is urged in a clockwise direction by 25 means of a spring 81 supported at its one end on a pin carried by arm 82 on bellcrank 75 and at its other end on a pin 83 secured on frame member 66.

In normal cyclic operation of the meter 12, bellcrank 30 75 is rocked to-and-fro to prevent engagement of pin 79 with the shoulder 80 of arm 77 or the abutment of the pin with the end of the arm 78. To control the oscillation of the bellcrank 75, a link 84 is pivotally supported at its one end at 85 on arm 82 of bellcrank 75 35 and is supported adjacent its other end for reciprocative movement by means of a slot therein in engagement with pin 70 on frame member 66. At its free end, link 84 is provided with a lip formed at a right angle thereto, the outer surface 86 of which is adapted for engagement by 40 a pin 87 secured on the driven pulley 62, during each cycle of rotation of the pulley.

In the full-cycle position of the drive pulley 61, carried 45 by print-head shaft 23, the pin 79 is in the position indicated by dash line in FIG. 2. At this same time, pin 87 carried by the driven pulley 62, secured on register actuator shaft 60, is in the position indicated by dash line in FIG. 2, displaced approximately 210 degrees counter-clockwise from the position of the pin 79 on pulley 61. In this full-cycle position of the pins 79 and 87, spring 81 urges link 84 the extent of its movement to the right (FIG. 2), thereby maintaining shoulder 80 of arm 77 out of the path of rotation of the pin 79 to enable rotation of drive pulley 61 and therefore rotation of the print-head 16. Following a 180 degree rotation of print-head 50 60 16, the pins 79 and 87 are in the respective positions shown in FIG. 2, wherein pin 87 contacts the lip formed on the end of the link 84. During the subsequent 90 degrees rotation of drive pulley 61 and driven pulley 62, the pin 87 is effective to move link 84 to the left, 55 rocking bellcrank 75 counter-clockwise against the urgency of the spring 81 to remove the end of arm 78 out of the rotational path of travel of pin 79, as seen in FIG. 3. Thus, an uninterrupted cycle of meter operation may be completed.

If, at any time during the initial 180 degree rotation 60 of the drive pulleys 61 and 62, the teeth should be stripped from belt 63 or the belt should become severed, the bellcrank 75 will remain in the normally rocked position shown in FIG. 2. In this condition of the parts, pin 87 65 may assume any angular position in a counter-clockwise

direction from the dash line position shown in FIG. 2 to the full line position shown. During this partial cyclic rotation of the driven pulley 62, the digitation phase of the meter operation will not have been completed. At the same time, drive pulley 61 will continue its counter-clockwise rotation until pin 79 thereon abuts the ends of the arm 78 of bellcrank 75 to prevent further rotation of the print-head shaft 23, thereby enabling the well-known function of the conventional slip clutch within the machine drive system as described in Patent No. 3,107,854. It will be noted that the partial cyclic rotation of the print-head 16 and therefore pulley 61 counter-clockwise to the position wherein pin 79 engages the end of the arm 78 is not sufficient to effect a complete impression of the postage indicia die plate 71.

In the event the belt 63 becomes severed or the teeth stripped therefrom during any part of the cycle following 180 degrees to 210 degrees angular rotation of drive pulley 61 and the driven pulley 62, the indicia print-head 16 and toothed pulley 61 will continue rotation in a counterclockwise direction until pin 79 contacts shoulder 80 of arm 77 of bellcrank 75, remembering that pin 87 will have moved the link 84 to the left to position shoulder 80 in the path of rotation of the pin 79. Under this condition, the postage impression will have been made and the digitation phase of the cycle will have been completed so that the amount of postage registered in the selector mechanism will have been subtracted out of the descending register and accumulated in the ascending register. However, the tens-transfer phase of the operation may or may not have been completed.

Following a severance or stripping of the belt 63, the cover of the meter unit 12 must be removed by someone with authority to do so, and the broken or stripped belt 63 replaced by a new belt. In the first instance, i.e., where the meter operation has been terminated by the engagement of pin 79 with the end of arm 78 and after the meter cover has been removed, the toothed pulley 61 and therefore print-head 16 are rotated counterclockwise (FIGS. 2 and 3) to the full-cycle position and the register actuator shaft 60 is likewise rotated in a counterclockwise direction to the full-cycle position followed by the replacement of the belt 63. It will be noted that under the first condition the selected postage will remain locked in the selector mechanism, in a well-known manner, as fully described in the reference patent, No. 3,107,854. Consequently, as the register actuator shaft 60 is rotated to its full-cycle position, the amount of postage indicated in the selector mechanism will be entered into the descending register and the ascending register followed by the tens-transfer phase in each register to complete the operation.

In the second instance, even though the indicia print-head 16 returns to its full-cycle position wherein it becomes locked by virtue of the engagement of pin 79 with the shoulder 80 of arm 77, the digitation phase of the cycle of operation will have been completed and the value in the selector mechanism will have been entered into both the descending and ascending registers. However, the register actuator shaft 60 must be restored counterclockwise (FIGS. 2 and 3) to its full-cycle position before installation of a new belt. During the restoration of register actuator shaft 60 to its full-cycle position, the tens-transfer phase of the operation will be completed.

What is claimed is:

1. A drive mechanism for a postage metering machine comprising a rotative driving member, means for controlling cyclic operation of said rotative driving member, a rotative member driven in cyclic timed relation to said drive member, a belt means operatively connecting said driven member with said driving member, and a normally inoperative locking means rendered operable by said driven member in each of certain angularly rotated posi-

tions thereof to lock said driving member in a corresponding predetermined one of a plurality of angularly rotated positions upon severance of said belt means.

2. A drive mechanism for a postage metering machine comprising a toothed drive pulley, a cyclically operable means for imparting rotation to said drive pulley, a toothed driven pulley, a timing belt connecting said driven pulley with said drive pulley operable to drive said driven pulley in synchronism with said drive pulley, means positionable to lock said drive pulley in either of two rotated positions, and means normally controlled by said driven pulley operable to disable said locking means during cyclic rotation of said driven pulley in timed relation to the rotation of said drive pulley and operable upon driving detachment of said belt with said pulleys to effect operation of said locking means in a predetermined rotated position of said drive pulley.

3. In a drive mechanism, the combination of a cyclically operable drive pulley, a driven pulley, means normally drivingly connecting said driven pulley with said drive pulley, means for locking said drive pulley against rotation following a full or partial cyclic rotation thereof, and means controlled by said driven pulley during rotation thereof for preventing operation of said locking means and operable upon detachment of said connecting means to enable operation of said locking means to lock said drive pulley in a predetermined one of said two cyclically rotated positions.

4. In a drive mechanism, the combination of a cyclically operable drive pulley, a driven pulley, a belt means drivingly connecting said driven pulley with said drive pulley, a positionable means operable in each of a plurality of positions to lock said drive pulley against rotation following each of a plurality of predetermined angular rotations of said drive pulley, and control means associated with said driven pulley normally operable during rotation of said driven pulley to prevent operation of said positionable means and effective to enable the operation of said positionable means for locking said drive pulley in an angularly rotated position thereof corresponding to the angularly rotated position of said driven pulley upon driving disablement of said belt means during cyclic rotation of said drive pulley.

5. In a drive mechanism, the combination of a toothed drive pulley, a cyclically operable driving means for said drive pulley, a toothed driven pulley, a timing belt drivingly connecting said driven pulley with said drive pulley, a lock means rockable to each of two locking positions during cyclic rotation of said drive pulley, resilient means normally biasing said lock means to one of said two positions, means associated with said drive pulley for rotation therewith operable to lockably engage with said lock means in either rocked position thereof following a predetermined angular rotation of said drive pulley, and means normally controlled by said driven pulley during rotation thereof operable to control the rocking of said lock means alternately between said two positions in timed relation to the rotation of said drive pulley to prevent engagement of said associated means with said lock means and effective upon driving disablement of said timing belt during cyclic rotation of said drive means to enable said lock means to lock said drive pulley against rotation in an angularly rotated position corresponding to the angularly rotated position of said driven pulley.
